UNITED STATES PATENT OFFICE.

LEMUEL COBURN, OF HOLYOKE, MASSACHUSETTS.

MACHINE FOR BENDING SHEET METAL.

SPECIFICATION forming part of Letters Patent No. 390,346, dated October 2, 1888.

Application filed February 10, 1888. Serial No. 263,606. (No model.)

To all whom it may concern:

Be it known that I, LEMUEL COBURN, a citizen of the United States of America, residing at Holyoke, in the county of Hampden and State of Massachusetts, have invented new and useful Improvements in Machines for Bending Sheet Metal, of which the following is a specification.

This invention relates to machines for bending metal in parallel longitudinal folds; and it is particularly applicable for use in the manufacture of trolley-tracks, such as are illustrated and described in Letters Patent of the United States granted to me June 21, 1887, No. 365,240; but, as will appear from the description hereinafter given, it embraces certain constructions and contrivances common to and applicable in machines for bending metal for other purposes; and the invention consists in the constructions and combinations of parts, as will hereinafter fully appear and be set forth in the claims.

In the accompanying sheets of drawings, Figure 1 represents in side elevation and partial central longitudinal vertical section a machine for bending flat strips of sheet metal into the form desired and suitable for trolley-tracks; and Fig. 2 is a plan view of the lower portion thereof, which is below the plane indicated by line *v v*, Fig. 1. Fig. 3 represents an enlarged detail view in horizontal section on line *w w*, Fig. 1. Fig. 4 represents in perspective and enlarged a section of a sheet-metal trolley-track, such as may be formed under the operation of the present improved sheet-metal-bending machine. Figs. 5, 6, and 7 are enlarged vertical cross-sectional views of the die portions of the machine respectively on lines *x x*, *y y*, and *z z* of Figs. 1 and 2, there also being indicated thereupon or in relation thereto the cross-section of a strip of sheet metal in the various phases thereof which it possesses or is made to possess under the action of the various parts of the machine. Fig. 8 is an enlarged view, in perspective, of a portion of the length of the draft or hook rod, to be hereinafter referred to; and Fig. 9 is a perspective view of a strip or blank of sheet metal of a form suitable for the production of the trolley-track.

The present machine comprises three sets of dies, A, B, and C, each comprising the lower

portion, within or upon which the sheet-metal strip is disposed, and the upper portion forming or attached to a vertically-reciprocating plunger, and the several die parts are ranged and aligned longitudinally, as shown. 55

As to the set of dies A, (see Fig. 5,) the purpose of which is to convert the sheet-metal strip from the flat form shown in Fig. 9 into the **U** form indicated by dotted lines, Fig. 5, and the black cross-section, Fig. 6, the lower or female die, *a*, thereof consists of a longitudinal metal trough, of substantially **U** shape in cross-section, with its opposite walls for a portion of its height vertical, as shown, and thence preferably outwardly flaring, as seen at *b*, and at the upper edge of each flaring side wall horizontal wings or shelves *c* may be provided, and the upper or male die of this set of dies is transversely of rectangular form, as shown. 70

The set of dies B, (see Fig. 6,) which is for converting the **U** or trough-formed strip into the form of a tube with transversely-rectangular walls, as indicated by dotted lines in said figure, and the black cross-section, Fig. 7, as to its lower die, consists of a longitudinal trough-shaped body, *d*, having horizontal bottom and vertical side walls, *e*, with converging upper edges, *f*, within which is disposed a parallel core or wrapping-bar, *g*, and the upper die, *h*, of said set of dies B is on its under side formed with a horizontal central portion, *i*, and downwardly and outwardly diverging extensions *j*, 85 as shown, said horizontal portion *i* being of a width about equal to the distance between the side walls of the **U**-strip of metal which is to surround the core-bar *g*, and said flaring extensions *j* being formed to lie, when said upper die is down, outside of the converging and inclined edges *f* of the trough-body of the lower die. 90

The set of dies C, (see Fig. 7,) which is for converting the rectangular tubular strip, as seen in the black cross-section, Fig. 7, to the form indicated in said figure by dotted lines, and as seen in Fig. 4, as to its lower die, *o*, consists of a substantially rectangular trough-shaped body, with the upper inner edges, *k*, of its side walls curved inwardly, as shown, within which is disposed a parallel core-bar, *m*, of similar shape and size to the core-bar *g* of the die B, but having in its upper side a longitudi-

nally-extending depression or recess, *l*, and the upper die, *n*, of said set of dies C is provided with a downwardly-extending longitudinally-arranged rib, *p*, exteriorly corresponding to 5 the walls of the depression *l* in said core-bar *m*.

The longitudinally-aligned lower dies, *a d o*, have in their bottom surfaces a groove, *q*, extending continuously therethrough, and within which is placed a draft-rod, *D*, adapted for a 10 back-and-forth endwise play therein. Said draft-rod at its rear end is provided with a rigid hook or dog, *r*, and intermediate of its length it is provided with pivoted dogs *s s*, having bearings within recesses *t* of the draft- 15 bar, said pivoted dogs being weighted at their rear ends, so that normally their forward ends or noses, *u*, stand above the upper side of said draft-bar, and said dogs are so adjusted on the draft-bar that when the bar is in its normal 20 position, as seen in Figs. 1 and 2, the said dogs *r s s* will stand in positions back of and against the rear ends of the central bottom portions of the sheet-metal strips when in their 25 respective places in the lower dies of the die- sets A, B, and C, as occurs in the operation of the present machine; and said draft-rod *D* at its forward end is provided with a cross-head, 10, and a ring-eye, 11, and to the said cross-head one end of a rope, 12, is attached, which 30 passes rearwardly around a sheave, 13, thence forward to and around a drum, 14, and rearward to an engagement with said ring-eye 11 of the draft-bar, as shown in Fig. 1.

The bottom faces of the core-bars *g m* are 35 longitudinally recessed, as at 15, to permit the passage of the dogs *s s* in the forward movement of the draft-rod, it being understood that in the return movement of said draft-rod said dogs are depressed below the upper surface of the draft-rod when passing under strips of metal in the trough-bodies *d o*, through which they travel.

The side walls, 16 17, of the trough-bodies of the lower dies of the sets of dies B C are 40 formed of wedge shape or tapering in their length, as seen in Fig. 2, and said side walls are intended to be drawn out a short distance, thereby widening the spaces between said side walls and the core-bars, releasing the bind 45 upon the metal formed thereat, and the core-bar *m* of the lower die of the set C is made in two parts—an upper part, 18, and lower part, 19—each tapering as to vertical thickness, as shown in Fig. 1, so that when the upper portion, 18, is drawn endwise forward the height 50 of the core-bar *m* is decreased, permitting a release from vertical bind of said bar upon the sheet-metal strip folded thereabout, as shown. The lower portion, 19, of said core-bar 55 *m* is jointed to the core-bar *g* in any suitable manner—for instance, “halved together” therewith, as seen at 20, Fig. 1; and said wedge-shaped side walls, 16 17, are also jointed to move in unison and for convenient endwise 60 movement of said tapering portions 16 and 17 and 18 of the dies. Levers 21 and 22 are fulcrumed in suitable fixed bearings, 23 and 24,

of one of the uprights, *E*, of the machine, the said lever 21 by its lower slotted end engaging a pin of the wedge-wall 17, and the lever 2 70 by its lower slotted end engaging a pin of the movable tapering part 18 of core-bar *m*. The said core-bar *g* at its rear end is suspended a slight distance above the bottom of the trough-body of the lower die of the set B by the engagement therewith of a vertical bolt, 25, projecting upwardly and loosely through an aperture, 26, of a horizontal web, 27, of the branched base of one of the uprights, *E*, said bolt being surrounded between its head and said web by 80 a stiff spiral spring, 29. The vertical position of said suspended end of the core-bar *g* is adjusted by the interposition of the washers 28 about said bolt between the upper side of said bar *g* and the lower side of the web 27. 85

The male die of the set of dies A is provided at its under face near each end with vertical downwardly-tapering pins 30 in central longitudinal alignment, which are for the purpose of entering the centrally-aligned holes 31 90 in the blank *G* of sheet metal to be bent for maintaining it centrally in the die for a uniform and symmetrical bending, and the draft-bar *D* has holes 32 to permit the entrance therein of said centering-pins 30.

As will be particularly seen on reference to Figs. 1 and 3, each plunger-die is formed with a vertical groove, 33, at its ends, into which a tongue, 34, of a V-edged bearing-block, *F*, enters, the said V-shaped bearing-blocks playing vertically in corresponding V-shaped grooves, 35, of the standards *E*. The tongue 34 of each V bearing-block is provided with horizontally-extending slots 36, through which bolts 37 extend, as also through the walls of 105 the plunger-body at each side of the groove 33, said bolts being headed and provided with nuts for securing said blocks in place. The said blocks have vertical walls or shoulders 47 extending laterally beyond the faces of the tongues 34, and between said shoulders 47 and the inclined ends 38 of the plunger-bodies wedges are driven, which serve to force said blocks to a close bearing at all times. Said wedges 39 are to be retained in place by the overlying nuts, washers, or heads 40 of bolts 41, which 110 pass through the bodies of the wedge-blocks, as shown. The plungers are to be raised and held and then lowered or allowed to descend in any desired or approved manner. As shown, the plungers are supported by ropes or chains 42 from drums carried on an overhanging shaft, 43. Said plungers are intended to be raised by the rotation of said shaft, and when at the proper height be held by dogs 44, which 115 are arranged on an oscillating shaft, 45. A spring, 46, suitably applied to the shaft 45, exerts a force to swing the said dogs into the vertical plane of travel of the plungers to support them. On an oscillation of the dog-carrying 120 shaft in the proper direction by the lever or crank 51, said supports are removed and the plungers are allowed to descend under their own weight, their elevating-ropes 42 being al- 125

lowed to unwind from the overhead drums, which are allowed to rotate with or on the said shaft 43, some well-known form of releasing-clutch devices being preferably applied on 5 said shaft, and so that the rotation of the shaft 45 may be limited, so that the dogs 44 thereon will be normally held to and limited in their die-supporting positions. A stop, 54, is suitably fixed on the side of one end standard, E, 10 against which the crank-lever 51, rigidly attached to and as one with said shaft, may abut, as indicated in Fig. 1.

The operation of the machine herein described is as follows: A blank sheet of metal, 15 as G, is first placed lengthwise on the shelves e of the lower die of the set of dies A. The plunger is then allowed to drop, forming the strip of metal into the U shape. Then on raising the plunger and moving the draft-rod D 20 endwise, as described, by the engagement of the rear hook, r, with the end of the bottom of the U-formed strip, the latter is carried horizontally endwise and made to telescope the core bar g of the lower die of the set B, 25 when the draft-rod is returned to place. Then, on the descent of the plunger h of said set of dies B, the said U-strip is converted into the form of a transversely-rectangular tube. Then, on withdrawing the side wedge-walls, 16 and 30 17, and moving the draft-rod forward by its intermediate dog, s, the said tubular-formed strip is carried horizontally endwise and made to telescope the core-bar m. The said wedge-walls are then returned to their closed positions, and on the descent of the upper die or 35 plunger of the set of dies C the meeting edges of the strip are turned inwardly and parallel with the side walls, as seen in Fig. 4. Then, on sliding the wedge side walls and also the 40 upper inclined or tapering part, 18, of core-bar m, and drawing out the draft-rod D, the completed trolley-track strip is by the outer hook, s, carried out of the lower die of the set C. In practice the upper dies are all intended 45 to be moved in consonance with each other, there being a sheet of metal to be bent as described, placed on or in the lower die of each of the set of dies A B C.

Other means for making the side walls, 16 50 and 17, adjustable than by forming them with outer inclined sides, as described, may be substituted as equivalents thereof—as, for instance, by having said separable side walls supported on and carried by screws which are 55 suitably supported in threaded bearings and to be operated by worm-gears carried by a common shaft.

The formation of the lower die, a, of the 60 set A with the upper outwardly-flaring walls, b, as shown, is most advantageous, as it insures a gradual bending of the flat sheet of metal at the time of the impact of the upper die, obviating the liability of any shearing action or breaking of the metal at the lines of bend, and assuring, even in the bending of in-

terior sheet metal, most satisfactory and practical results.

What I claim as my invention is—

1. In a sheet-metal-bending machine, the combination, with a longitudinal trough-formed lower die having its bottom provided with centrally-aligned apertures, of a corresponding longitudinally-arranged male plunger-die provided with centrally-aligned pins 30, and guided for a play into and away from 75 said trough-formed die, substantially as and for the purpose described.

2. In a sheet-metal-bending machine, the combination, with a female die, a, having a horizontal bottom provided with aligned apertures and vertical side walls terminating in upwardly-flaring walls b b, of a longitudinally-arranged male plunger-die, substantially of 80 rectangular shape in cross-section, provided with centrally-aligned pins 30, and guided for 85 a play into and away from said lower die, substantially as and for the purpose described.

3. In a metal-bending machine, the combination, with a longitudinally-ranging female die having a longitudinal groove or way, q, 90 and a correspondingly-formed male plunger-die, of a slide or draft rod playing in said groove and provided at its rear end with a dog or hook, r, substantially as and for the purpose described.

4. In a metal-bending machine, the combination, with a longitudinal female die having a longitudinal groove or way, q, and a correspondingly-formed male plunger-die, of a slide or draft rod playing in said groove, and provided at its rear end with a dog or hook, r, and a flexible connection by one end attached to the forward end of said draft-rod, thence passing to the rearward of the said forward end around a suitable guide, thence forward to and 100 around a rotatable drum, and thence rearwardly to an engagement with said draft-rod, substantially as and for the purpose described.

5. In a metal bending machine, the combination, with the die A, comprising the lower longitudinal trough part, a, having horizontal bottom and vertical side walls terminating in the upwardly-flaring walls b b, and the longitudinally-ranging male plunger-die, of the die 115 comprising the lower longitudinally-arranged trough part, d, the longitudinal core-bar of rectangular cross-section within said trough part d, and the plunger h, having horizontal bottom i, with downwardly-flaring wings j, 120 substantially as and for the purpose described.

6. In a metal-bending machine, the combination, with the die A, comprising the lower longitudinal trough part, a, having horizontal bottom and vertical side walls terminating in 125 the upwardly-flaring walls b b, and the horizontally-ranging male plunger-die, of the die B, comprising the lower longitudinally-arranged trough part d, having horizontal bottom and vertical side walls, one of which is laterally adjust- 130

able, the longitudinal core-bar of rectangular cross-section supported within said trough part *d*, and the plunger *h*, having horizontal bottom *i*, and downwardly-flaring wings *j*, substantially as and for the purpose described.

7. In a metal-bending machine, the combination, with a female die provided within one wall with a longitudinal groove or way, and a plunger-die of corresponding cross-section, and one or more sets of dies comprising lower longitudinally-arranged female dies provided within one wall with a longitudinal groove or way in continuation of said first-mentioned groove, and each provided with a longitudinal core-bar and plunger-dies, of a draft-bar, *D*, arranged for a slide in said continuous groove or way, provided with suitably arranged abutments, for the purpose described.

8. In a metal-bending machine, a trough and a plunger-die, and one or more sets of dies comprising lower longitudinally-arranged trough portions, one or more of said trough portions being provided with a separable side wall of wedge shape, suitably guided for a lengthwise movement, and the lever *21*, engaging said wedge-shaped side wall, combined with a longitudinal core-bar, substantially as and for the purpose described.

9. In a metal-bending machine, the combination, with the trough and plunger-die *A*, and a stationary standard or bracket, *27*, provided with an aperture, *26*, of the die *B*, comprising the longitudinally-arranged trough-body, the core bar *g* and plunger *h*, the headed bolt *25*, passing through said aperture *26* and connected to the end of said core-bar, and the spiral spring *29* and washers *28*, substantially as and for the purpose described.

10. The combination, with the trough and plunger-dies *A*, and the die *B*, comprising the lower longitudinally-arranged trough-body, *d*, having the movable inclined side wall, *16*, core-bar *g*, and plunger *h*, of the die *C*, comprising the lower longitudinally-arranged trough-body having movable side wall, *17*, jointed to said movable side wall *16*, core-bar *m*, consisting of the lower portion, *19*, having its upper face inclined, and the upper portion, *18*, having its lower face inclined and having the longitudinal depression *l*, and the levers *21* and *22*, the former engaging said inclined side wall, *17*, and the latter engaging said upper core-bar portion, *18*, substantially as and for the purpose described.

11. In a metal-bending machine, the combination, with uprights *E*, having vertical slideways *35* therein, of a plunger-die body having inclined ends *38* and vertical grooves *33* thereat, the bearing-blocks *F*, having the shoulders *47*, and tongues *34*, provided with the horizontally-extending slots *36*, the headed

bolts *37*, and the wedges *39*, substantially as and for the purpose described.

12. In a metal-bending machine, the combination, with uprights *E*, having vertical slideways *35* therein, of a plunger-die body having inclined ends *38* and vertical grooves *33* thereat, the bearing-blocks *F*, provided with the headed bolts *41*, and having the shoulders *47* and tongues *34*, provided with the horizontally-extending slots *36*, the headed bolts *37*, and the wedges *39*, substantially as and for the purpose described.

13. In a metal-bending machine, the combination, with suitable uprights, *E*, having vertical slideways therein, and one or more plunger-dies having bearings in said vertical ways, of a longitudinally-arranged spring-actuated rock-shaft, *45*, provided with fixed dogs adapted to be swung into the vertical plane of movement of said plunger-dies, and having the crank-lever *51* and the stop *54*, substantially as and for the purpose described.

14. In a metal-bending machine, in combination, the frame or uprights *E*, and the die *A*, comprising the lower trough portion, *a*, having horizontal bottom and vertical side walls terminating in the upwardly-flaring extensions *b*, and male plunger-die, of substantially rectangular cross-section, having the pins *30*, the die *B*, comprising trough-body *d*, having horizontal bottom and vertical side walls terminating in inwardly-inclining portions *f*, one of which side walls is laterally movable, the transversely-rectangular core-bar *g*, supported within said trough-body *d*, and the plunger-die *h*, having lower horizontal face, *i*, and downwardly-flaring wings *j*, and the die *C*, comprising the lower trough-body, *o*, having horizontal bottom and vertical side walls, one of which is laterally movable, the core-bar *m*, comprising lower tapering portion, *19*, jointed to said core-bar *g*, and the upper tapering portion, *18*, provided with the longitudinal depression *l*, and the male plunger-die *n*, having the rib *p*, the said core bar portions *g* *19* being provided on their under sides with the longitudinal way *15*, and the said horizontal bottoms of said lower trough portions, *a d o*, having the longitudinal way *q*, the draft-rod *D*, adapted to slide in said way *q*, having the aligned holes *32*, the rear hook, *r*, and the recesses *t*, within which are pivoted the counterweighted dogs *s*, the overhanging drum-shaft *43*, and the rope or chain supports between the drums and the plunger-dies, substantially as and for the purpose described.

LEMUEL COBURN.
